PROTECTIVE COVER FOR UNDERGROUND ELECTRICAL SERVICE CONNECTIONS

Saul Rosner, 8 Fairfield Terrace, Norwalk, Conn., and Marvin V. McCoy, 108 Pool Road, North Haven, Conn.

Filed Sept. 17, 1963, Ser. No. 76,621

Term of patent 14 years

(Cl. D26—5)

FIG. 1

FIG. 2

FIG. 3

FIGURE 1 is a top plan view of a protective cover for underground electrical service connections, showing our new design;

FIGURE 2 is a side elevational view; and FIGURE 3 is a bottom plan view.

We claim:

The ornamental design for a protective cover for underground electrical service connections, substantially as shown.
